Des. 214,580
Patented July 1, 1969

214,580

COMPARTMENTED DINNER TRAY

Robert A. Jones, Louisville, and Gordon A. Vold,
Anchorage, Ky., assignors to Anaconda Aluminum
Company, a corporation of Montana

Filed Aug. 12, 1966, Ser. No. 3,451

Term of patent 14 years

Int. Cl. D7—01

U.S. Cl. D44—10

FIG. 1

FIG. 2

FIG. 3

FIG. 4

FIG. 5

FIG. 1 is a perspective view of a compartmented dinner tray showing our new design;

FIG. 2 is a top plan view thereof;

FIG. 3 is a front elevational view thereof;

FIG. 4 is a side elevational view thereof; and

FIG. 5 is a rear view thereof.

We claim:

The ornamental design for a compartmented dinner tray, as shown.
